MULTIPLICATE WRITING INSTRUMENT

Stanley Ankud, 117 Noble St., Brooklyn 22, N.Y.

Filed Nov. 12, 1957, Ser. No. 695,582

2 Claims. (Cl. 120—42.13)

This invention relates to writing instruments and, more particularly, to a writing instrument having a plurality of manually actuated writing members retractably supported within the barrel thereof.

While various types of writing instruments have been provided that enable the user to selectively actuate the mechanism to eject one of a plurality of different writing members, such units often require a relatively large number of parts, require substantial maintenance, and are difficult to operate. Accordingly, an object of the present invention is to provide a multiplicate writing instrument that is extremely simple in construction, efficient in operation, and which will overcome the aforementioned difficulty.

Another object of the present invention is to provide a writing instrument that supports a plurality of different writing members within the lower barrel portion and has an automatically operative ejector mechanism supported within the upper barrel portion, whereby the particular writing member to be ejected can be selectively indexed by rotating the upper and lower barrel portions relative to each other.

A still further object of the present invention is to provide a multiplicate writing instrument of the type described that contains a minimum number of parts, is virtually foolproof, and can be manufactured in large quantities at relatively low cost.

All of the foregoing and still further objects and advantages of this invention will become apparent from a study of the following specification, taken in connection with the accompanying drawing, wherein:

Figure 1 is a perspective view of a writing instrument made in accordance with the present invention in operative use;

Figures 2a and 2b when combined are a longitudinal cross sectional view of the writing instrument shown in Figure 1, in a retracted position;

Figure 2c is an enlarged fragmentary cross sectional view, showing the cooperation between certain parts of the present invention;

Figures 3a and 3b define a view similar to that of Figures 2a and 2b, with the parts in an extended position;

Figure 4 is an enlarged fragmentary longitudinal cross sectional view through the cap of the instrument showing certain parts of the ejector mechanism; and

Figure 5 is a fragmentary exploded longitudinal cross sectional view of certain parts of the present invention, illustrating the manner in which the upper and lower barrel portions are rotatably engaged.

Referring now to the drawing, and more particularly to Figures 2a and 2b thereof, a writing instrument 10 made in accordance with the present invention is shown to include a lower barrel portion 12 and an upper barrel portion 13 which are rotatably secured together. A cylinder 15 having a plurality of circumferentially spaced apart longitudinal bores 16 is supported within a band 11 of the lower barrel portion 12. A single plunger 18 having an enlarged head portion 18a, is slidably supported within

2

each such longitudinal bore 16, each such plunger being urged toward a retracted position by means of compression springs 19 acting between the opposite ends of the cylinder 15 and the respective plunger 18. The outermost end of each plunger 18 is provided with a coupling member 17 for releasably engaging with the adjacent end of a writing member 20, such as a ball pen or pencil cartridge. The coupling 17 accommodates a limited amount of universal movement between the respective cartridge 20 and plunger 18, to enable the cartridge to angle slightly as it is ejected from the lower barrel portion, in a manner hereinafter described. A guide pin 21 extends centrally between the respective cartridges 20 and has a bushing 23 that is slidably engaged by and maintains the cartridges in proper spaced apart and parallel relationship when in the retracted position shown in Figure 2b, this guide pin 21 being substantially concentric with the outer end opening 22 in the lower barrel portion 12 through which the cartridges are extended.

The cylinder 15 is secured within the band 11 that has a reduced portion 17' upon which the lower barrel portion 12 is carried. The outermost portion 14 of the cylinder 15 is radially outwardly enlarged to define a cylindrical surface with the facing end of the band 11, upon which a friction sleeve 26 and bearing sleeve 29 are mounted.

The upper barrel portion 13 receives and is secured to the exterior of a connector sleeve 25, within which a main sleeve 24 of the ejector mechanism is secured. Thus, the integrally connected outermost portions of the upper barrel 13 and connector sleeve 25 form a single cylindrical terminal portion 13' that slidably receives the outermost portion 14 of the lower barrel portion 12 therewithin together with the bearing sleeve 29 and associated friction sleeve 26, as is shown in Figure 5. The frictional engagement between the friction sleeve 26 of the lower barrel portion 12 and the terminal portion 13' of the upper barrel portion 13 is such as to allow relative rotation between the upper and lower barrel portions for color selection purposes, as will be hereinafter more fully described. An actuator block 27 is slidably supported within the main sleeve 24 for reciprocating longitudinal movement. A compression spring 28 acting between the cylinder 15 and the actuator block 27 normally urges the actuator block and associated elements toward a retracted

position shown in Figures 2a and 2b. An ejector rod 31 is slidably supported relative to the actuator block 27 and which is also supported within the main sleeve 24 for reciprocating longitudinal movement relative to the upper barrel portion 13 for engagement with a selected one of the plungers 18 to which the selected writing instrument cartridge is connected. The exterior of the rod 31 has a groove 31' that slidably engages a guide rail 24' of the main mounting sleeve 24, to thus prevent twisting of the rod 31 during the longitudinal actuation thereof. The exterior surfaces of the relatively rotatable barrel portions 12, 13, such as the band 11, can be imprinted with suitable indicia to indicate the color of the cartridge with which the ejector rod is aligned so as to enable the user to select a writing member of any of the available colors.

By rotating the upper barrel portion, within which the actuator block 27 and ejector rod 31 are secured, relative to the lower barrel portion, the ejector rod 31 can be selectively rotated to engage any one head 18a of the plurality of plungers 18 so as to actuate the selected cartridge in the manner now described.

A push button 33 extends outwardly through the outer end opening 32 in the upper barrel portion 13 and is integral with the shank 34 of an ejector head 35 that is slidably supported for reciprocating longitudinal movement within the main sleeve 24. A stop pin 36 limits the outward movement of the head 35 which is normally biased toward the position shown in Figure 2a

by the action of the compression spring 28 acting through the actuator block 27 which is integrally connected to and forms a part of the head 35. A main link 37 is pivotally connected at its free end, by means of a pivot pin 38 to an intermediate portion of the actuator block 27 and head 35 assembly, which portion has a stop member 44 for engagement with a shoulder 46 defined by the main sleeve 24. The opposite end of the link 37 is pivotally connected to an auxiliary link 41 by means of a similar pivot pin 40, and the opposite end of the auxiliary link 41 is pivotally connected to the head 43 of the ejector rod 31 by means of a separate pivot pin 42. With reference now to Figures 3a and 3b of the drawing, the movement of the actuating linkage will be understood. As the push button 33 is depressed, the links are displaced but not rotated by the longitudinal movement of the head 35 until the stop 44 engages the shoulder 46, following which the continued movement of the head 35 is operative to rotate the main link 37 about its pivot pin 38 so as to fully extend the connected links 37, 41, during which full extension movement, the plunger 31 is operative to fully extend the associated cartridge 20 to the operative position 20a shown.

With reference now to Figure 4 of the drawing, a latch mechanism is shown which is operative to retain the selected cartridge in the extended position after the push button has been depressed and released until it is desired to again retract the extended cartridge. This mechanism is shown to include a latch member 48 which is pivotally mounted by means of a pin 49 to the main sleeve 24 at one side of the path of movement of the main link 37. A leaf spring 50 carried by the main sleeve 24 overlies the latch 48 and urges it toward the normal horizontal position shown. A release pawl 52 is pivotally mounted upon the head 35 by means of a pivot pin 53 and is normally biased toward a horizontal position by the action of the associated leaf spring 55 that is secured to the main sleeve 24. During the forward movement of the shank 34 and the head 35, an enlargement 56 integral with the main link 37 will pass beneath the latch 48 which will secure the link 37 in the extended position since the spring 50 tends to prevent the latch 48 from allowing the link 37 to return. During this forward movement, the engagement of the rear corner 51 of the facing side of the link 37 with the release pawl 52 maintains it in the upwardly inclined position until after the link 37 has been locked beneath the latch 48. However, upon release of the push button, the release pawl 52 will be withdrawn from engagement with the corner 51 and urged toward the longitudinally extending position 52a by the action of the spring 55 so that upon the next pushing movement of the push button 33, the release pawl 52 will lift the latch 48 as the pawl engages the inclined facing surface of the latch 48 to enable the enlargement 56 and the link 37 to be withdrawn under the action of the compression spring 19 which urges the entire head assembly 35 and associated linkage toward the outer end of the upper barrel portion. It will thus be recognized that the first actuation of the push button will extend the selected cartridge, while the subsequent actuation of the push button will effect the retraction thereof. Any particular cartridge may be selected by rotating the upper and lower barrel portions relative to each other to the desired position, as indicated by any suitable indicia which may be imprinted upon the band of the writing instrument.

While this invention has been described with particular reference to the construction shown in the drawing, it is to be understood that such is not to be construed as imparting limitations upon the invention, which is best defined by the claims appended hereto.

Having thus described my invention, I claim as new and desire to secure by Letters Patent:

1. A multiplicate writing instrument comprising, in combination, a lower barrel portion having an outer end opening and an upper barrel portion having an outer end opening, said upper and lower barrel portions being rotatably secured together, means supporting a plurality of circumferentially spaced apart writing members for longitudinal movement within said lower barrel portion, ejector means within said upper barrel portion, means for manually operating said ejector means to releasably eject and retract a selected one of said writing members through said outer end opening of said lower barrel portion, said means for supporting said writing member within said barrel comprising a cylinder having a plurality of circumferentially spaced apart longitudinal bores, a coupling supported within said bore for reciprocating longitudinal movement, a writing member secured to each said coupling for movement between a completely enclosed position within said lower barrel portion and a partially extended position through said outer end opening of said lower barrel portion, each of said coupling connecting said associated writing member for limited universal movement for accommodating angular movement of said writing member relative to said lower barrel portion, each said coupling including a plunger extending in a direction away from said associated writing member toward said ejector means, said ejector means comprising a rod supported within said upper barrel portion for reciprocating longitudinal movement parallel to the longitudinal axis of said cylinder into engagement with a selected one of said plungers, said rotation of said upper barrel portion relative to said lower barrel portion being operative to align said rod with a predetermined one of said plungers to index said ejector means for the ejection of a selected one of said writing members, said means for normally operating said ejector means comprising a push button slidably supported within said outer one of said upper barrel portion, and linkage connecting said push button to said ejector rod.
2. A writing instrument as set forth in claim 1, wherein said linkage comprises means for selectively retaining said ejector rod in a completely extended and completely retracted position, and spring means acting upon said linkage normally urging said push button toward a normal retracted position.
